SIGNALING SYSTEM

Noël Meyer Rust, Chelmsford, England, assignor
to Radio Corporation of America, a corporation
of Delaware

Application May 5, 1936, Serial No. 77,913
In Great Britain May 11, 1935

1. Claim. (Cl. 178—6)

This invention relates to electrical energy transmission systems and more particularly to cable systems for transmitting television and like signals.

5 Serious difficulties arise in seeking to transmit television signals over cable lines, these difficulties being due to the very wide range of frequencies involved, the said range extending in many modern high definition systems from 25 cycles per second, or even lower, to 2½ megacycles or higher. It is in practice so expensive as to be commercially impracticable to design and manufacture long cables which will introduce constant time delay over such a very wide range 10 of frequencies extending down to 25 cycles per second, or lower.

According to this invention, television or like signals are transmitted over cables designed to give substantially constant time delay for all the signal frequencies above approximately the scanning line frequency, and at the receiver end the lower frequencies below the minimum frequency over which the cable transmission system gives constant time delay, and in particular 20 the framing frequency and near frequencies, are separated out, subjected to a time delay corresponding to one or more picture frame periods and are then combined with the higher frequency signals, and fed to the receiver proper.

30 The invention may be carried into practice with cable systems consisting of relatively cheap small co-axial conductor high frequency cables of the air spaced type, and such cables when used in systems having repeaters every 20 kilometres or so, may be designed to give practically constant time delay over all television signal frequencies 35 above about 6 kilocycles (in television systems wherein twenty five 250 line pictures are transmitted per second, the scanning line frequency is 6250).

40 The invention is illustrated in the accompanying drawing which shows in block diagram form one way of carrying out the invention.

Referring to the drawing, 1 represents a television transmitting station (operating for example, with twenty five 250 line pictures per second) from which all the television signals from the framing frequency (25 cycles per second) upward are transmitted over a high frequency 45 cable transmission system such as that above described and equipped with cables 5 with inserted repeaters 3 having the usual amplitude correcting arrangements every 20 kilometres or thereabouts, and at the receiving end of the cable 50 system the channel is branched out into two

branches 7, 9, the branch 7 accepting the applying amplitude correction to all signals of a frequency equal to or above the scanning line frequency (6250 cycles per second in the present example) but rejecting all frequencies below the 5 said scanning line frequency. This may, for example, be a high pass filter. Suppose the whole transmission system up to the output terminals of the branch 7 imposes a constant time delay t_1 upon all frequencies equal to, or above, the scanning line frequency; then the other branch 9 is arranged to accept the low frequencies (the framing frequency and what may be termed the "floating zero" frequencies which define the general level of illumination) to impart thereto a 10 constant time delay equal to $t_1 + np$ where n is a whole number, and p is the number of pictures or frames per second. It will be appreciated that it may be, for example, a low pass filter.

20 The outputs from the two branches are combined and fed at 11 to a television receiver or, if the signals are to be transmitted further, to a television signal "rediffuser". Thus, in the system now described where twenty five 250 line pictures are transmitted per second, the branch 7 could be arranged to pass the band 6250—1, 500,000 cycles per second and the branch 9 to pass a band 10—50 cycles per second. If desired, the upper limit of the band passed by the branch 25 9 may be extended above about 50 cycles so as to pass also one or more of the harmonics of the picture repetition or framing synchronizing frequency. This will facilitate the obtaining of sharp and accurate synchronization by passing the harmonics necessary to the obtaining of sharp pulse formation. It will be readily appreciated that in order to maintain correct phasing of the various components of the signaling current, phase correcting networks of the type well known in the art may be inserted before the repeaters or suitable phase correcting networks 30 may be connected in series with the high pass and/or low pass filters. Apparatus suitable for performing the requisite functions at 1, 3, 7, 9, and 11 is well known per se to those skilled in the art and it is, therefore, unnecessary to describe it herein. For example, the transmitter may be of the type disclosed in the Smith Patent No. 2,132,655, issued October 11, 1938 and entitled "System for producing electrical impulses" while the repeaters may be of the type shown in Smith Patent No. 2,045,315 which issued June 23, 1936, for "Amplifiers". The filters 7 and 9 may be any 35 one of the type described in the book entitled 40

45 50 55 "Amplifiers". The filters 7 and 9 may be any one of the type described in the book entitled

"Transmission Networks and Wave Filters" by Shea, Van Nostrand Co. (1929) New York City, while the receiver may take the form shown by the Osbon Patent No. 1,934,321 issued November 5, 1933 for Cathode ray oscilloscopes.

It will be seen that in the system as just described television signals between about 50 cycles and 6250 cycles per second, will be lost so far as the receiver is concerned but in practice this loss 10 is not serious. The extent to which signal frequencies may be permitted to be lost in this manner is a matter of degree, and it will be appreciated that the invention provides a compromise between the divergent requirements of utilizing 15 fully all the picture signals and satisfactorily transmitting television signals over a reasonably economical transmission line system.

Having now described my invention what I claim is:

An electrical energy transmission system for television signals comprising a cable transmission system adapted to give a substantially constant time delay t_1 , for all the television signal frequencies above approximately a predetermined frequency, an output and input end for said system, segregating means at the output end of said system for separating out television signal frequencies including a second predetermined frequency p , means for imposing a time delay t_1+np (where n is a whole number) upon said separated frequencies, and means for combining the separated, delayed, low frequencies with the frequencies above that for which said cable system imposes substantially constant time delay to produce substantially constant time delay for the picture signal frequencies above and below the predetermined frequency. 5 10 15
